UNITED STATES PATENT OFFICE.

CARL F. SCHEFFER, OF DAYTON, OHIO.

SECTIONAL APPARATUS FOR GENERATING AMMONIA-GAS FOR DRY-CLEANING MACHINES.

1,367,718.

Specification of Letters Patent.

Patented Feb. 8, 1921.

Application filed November 12, 1917. Serial No. 201,723.

To all whom it may concern:

Be it known that I, CARL F. SCHEFFER, a citizen of the United States, residing at Dayton, in the county of Montgomery and 5 State of Ohio, have invented certain new and useful Improvements in Sectional Apparatus for Generating Ammonia-Gas for Dry-Cleaning Machines, of which the following is a specification.

10 This invention relates to new and useful improvements in sectional apparatus for generating ammonia gas for dry cleaning machines.

The principal object of my invention is 15 to provide a sectional apparatus adapted to generate and continuously deliver to one or more dry cleaning machines, ammonia gas free from moisture. It has been found that ammonia gas introduced in a constant manner to a dry cleaning machine, will not support combustion, thereby eliminating the danger of igniting the benzin gases.

Ammonia regenerators now in use for other purposes, are not well adapted for application to dry cleaning machines, for the 25 reason that their valves and other connecting parts are inefficient and short lived when conveying ammonia gases for dry cleaning purposes.

30 My improved apparatus, on the other hand, eliminates valves and provides generating and delivering parts which are especially constructed with a view to delivering a continuous and uniform supply of ammonia gas free from moisture. Furthermore, my improved apparatus is sectional in nature, so that by adding generating units, any number of dry cleaning machines may be supplied without the necessity 35 of attaching an apparatus to each machine as under the former method. Thus a continuous supply of ammonia gas free from moisture may be delivered to each machine, to prevent the alkaline qualities of the 40 cleaning solution from being destroyed or neutralized by the greases contained in the garments to be cleaned. Furthermore, a continuous supply of anhydrous ammonia delivered to each machine, reduces the friction 45 between the cleaning solution and the garments, by acting as a lubricant, in that the grease and dirt in the garments to be cleaned are saponified thereby.

Another object of the invention is to prop-

erly balance the radiating and cooling surfaces of the device so that it will be possible to keep the aqua ammonia in the ammonia chambers at a temperature far below the boiling point of water, to prevent commingling water vapors being formed.

Other important and incidental objects will be brought out in the following specification and particularly set forth in the subjoined claims.

The preferred form of embodiment of my 65 invention is illustrated in the accompanying drawings, of which Figure 1 is a front elevational view of my improved apparatus. Fig. 2 is a side elevational view thereof, showing in dotted lines one of the units 70 about to be removed from the frame. Fig. 3 is a vertical sectional view taken through one of the units and its supporting parts. And Fig. 4 is a detail view of the slotted upper end of the discharge tube.

75 Throughout the specification and drawings similar reference characters denote corresponding parts.

In a detailed description of the preferred form of embodiment of my invention, the 80 numeral 1 designates one side member and 2 the other side member of a standard for removably supporting the generating units to be hereinafter described.

Extending between the side members 1 85 and 2 a slight distance above their bottom ends is a transverse steam chamber 3 preferably constructed of cast iron.

One end of the steam chamber 3 has a steam inlet 5 to receive a standard steam 90 pipe 5a. At the bottom of said steam chamber there is a steam exhaust 6.

Referring to Figs. 1 and 3, the chamber 3 is provided with two circular openings 7, although a greater number may be provided 95 to receive additional units if desired. Surrounding each opening 7 is a preferably circular flanged seat 8 adapted to receive a circular base 9 having a hollow chamber 10 extending downwardly therefrom into the 100 steam chamber 3. The base 9 has a central boss 11 to receive a vertical member 12 preferably circular in cross section and threaded on both ends. Extending through this member and the base 9, for communication 105 with the chamber 10, is a small hole 13 and a large hole 14. The latter receives at its top portion a vertical discharge tube 15,

while the hole 13 serves as an inlet for the liquid ammonia.

Adapted to be screwed on the upper threaded end of the vertical member 12 is an elongated vessel 16 preferably constructed of cast iron. Each vessel 16 consists of a lower chambered portion 17 and an upper chambered portion 18 connected together by an elongated neck 19.

10 Each vessel 16 is provided at its lower end with a threaded boss 20 to receive the threaded upper end of the member 12, from which the discharge tube 15 is adapted to extend upwardly into the chambered portion 17 of said vessel for a purpose to be herein-after described.

15 The construction which forms the upper support for the vessel 16 will now be described. Extending outwardly from the transverse member 4 are two bosses 21, each of which is in vertical alinement with its respective opening 7 in the steam chamber 3. Each boss 21 has a hollow exterior portion into which extends a narrow outlet tube 22 that makes an upward bend through the solid portion of the boss for communication with a tube 23 leading to a dry cleaning machine (not shown) for the purpose of delivering a continuous flow of ammonia 20 gas thereto.

25 The chambered portion 18 of the vessel 16 terminates at its rear upper end in a tubular fitting 24 whose outer end is formed to enter a respective boss 21 to firmly hold 30 the vessel within the frame and bring the angle conduit 25 within said fitting, in communication with the outlet tube 22 in said boss.

35 For the purpose of firmly holding the fitting 24 in the boss 21, there is provided a clamp consisting of two arms 26 connected at their outer ends by a head-piece 27 containing an interior groove adapted to fit over a shoulder 28 on the rear portion of the fitting 24. Each arm 26 is pivotally secured 40 to the boss 21 so that they may be moved, after the fitting 24 is connected to the boss, to bring the grooved head-piece tightly 45 against the shoulder 28. After it is in this position, a thumb screw 29 is adapted to be passed through the middle portion of the clamp headpiece 27, into the shoulder 28, to 50 fixedly maintain the fitting 24 in communicable engagement with its respective boss 21.

55 By withdrawing said screw, and swinging the clamp upwardly, the vessel is free to be tipped to the position shown in dotted lines in Fig. 2, for removal from the frame. After its upper end is so released, the vessel may be easily withdrawn for refilling by 60 lifting the base 9 above its seat 8 on the chamber 3.

65 The chambered part 18 of each vessel 16 has a vertical channel portion 30 which terminates at its upper end in an outwardly flaring mouth 31. The latter is adapted to

be closed by an elongated stopper 32 preferably constructed of rubber.

Extending inwardly from the front wall of the chambered part 18 of each vessel 16, are preferably two inclined baffle plates 33 70 33, each of which contains an opening 34 to permit a ready flow of liquid therethrough when the vessel is being filled or emptied.

Projecting toward the plates 33 33 from the opposite side of the vessel 16, are preferably two inclined baffle plates 35 35 so constructed and arranged with reference to the baffle plates 33, 33, as to coöperate with them in thoroughly baffling or mixing the ascending ammonia gases before they enter the outlet conduit 25.

75 In order to effectively distribute in all directions, the gases which issue from the top of the tube 15, the latter is provided with a series of superimposed slots 36 arranged around the periphery of the tube, the top thereof being closed by a threaded cap 37. (See Figs. 3 and 4).

80 In operation, after the apparatus is installed in a dry cleaning establishment, each generating unit is connected by a pipe 23 with a dry cleaning machine. The frame may be built of sufficient size to hold as many units as there are dry cleaning machines to be supplied, or to provide extra 85 spaces to receive additional units as additional dry cleaning machines are installed.

85 Each vessel 16 may be taken out of the frame in the manner before described, to be filled with aqua ammonia through its 90 mouth 31. The cork 32 is then applied and the vessel positioned in the frame so that the base 9 rests upon the seat 8 provided to hold the chamber 10 in one of the holes 7 of the steam chamber 3. The top portion of the vessel 16 is then secured to the top part of the frame as before described, by the clamping device directly above the hole 7 into which the base 10 of the vessel extends, so 95 that the conduit 25 will communicate with the bent tube 22 in the boss 24.

100 When the aqua ammonia is poured into the vessel 16, it will descend through the small hole 13 to the chamber 10 where it will be exposed to the steam in the chamber 3. 105 Although I preferably employ steam for heating this chamber, any other heat producing medium may be employed if desired. Being subjected to this heat, the liquid ammonia in the chamber 10 will soon come to a 110 state of ebullition, sending the generated gases upwardly into the vessel 16 through the large hole 14 and slotted discharge tube 15 with which the latter communicates. The hole 14 is made larger than the inlet hole 13, to cause the gas to feed up through it rather than through the latter. By the slots 36 provided in the upper end of the tube 15, the gas will be presented in a well commingled form to the baffle plates 33 and 35 in the 115 120 125 130

chambered part 18 of the vessel, by which it is further mixed and agitated.

My improved apparatus is so balanced that overheating of the aqua ammonia is prevented, thereby practically eliminating the possibility of water vapors finding their way into the upper portion of the vessel 16. However, those that might possibly do so are condensed by the baffle plates 33 and 35 and the reduced temperature of the upper portion of the vessel containing them. This balance is principally effected by the relatively small radiating surface presented by the chamber 10 as compared to the large 15 cooling surfaces of the chambered portions 17 and 18 of the vessel 16.

Furthermore, the fact that the vessel 16 is connected to its chambered base 10 by the narrow vertical member 12, also tends to 20 restrict the amount of heat transmitted to the vessel above; while the reduced neck portion 19 of the latter further restricts the amount of heat that would otherwise be transmitted to the upper portion 18 of said 25 vessel if it were of the same diameter throughout its length. Accordingly, any possible water vapors ascending to the upper portion of the vessel 16, will be so cooled thereby as to condense before they pass into 30 the outlet conduit 25.

It will now be seen that the ammonia gas will be practically freed of moisture by my improved apparatus, before it enters the conduit 25 therein for transmission by the 35 pipe 23 to its respective dry cleaning machine. Being delivered thereto in a moisture free and continuous manner, its cleaning properties are enhanced and danger from fire through the formation of static electricity is practically removed for the reasons heretofore given.

I do not wish to be limited to the details of construction and arrangement herein shown and described, and any changes or 45 alterations may be made therein within the scope of the subjoined claims.

Having described my invention, I claim:

1. In a device of the type specified, the combination with a frame, a heating chamber forming the bottom thereof, of an ammonia-containing vessel removably mounted in said frame, a gas outlet at the top of said vessel, a chambered base for the latter insertible into an opening in the heating chamber; a vertical member of reduced diameter, connecting said vessel and its base, a hole extending through said member to deliver ammonia to the base, a larger hole also extending through said member to receive the ascending gases, and a member in communication with the larger hole to discharge said gas in a diffused manner into the upper interior portion of said vessel.

2. In a device of the type specified, the combination with a frame, a heating cham-

ber forming the bottom thereof, of an ammonia-containing vessel removably mounted in said frame, a gas outlet at the top of said vessel, a relatively flat chambered base for the latter insertible into an opening in the heating chamber, a vertical member of reduced diameter connecting said vessel and its base, a hole extending through said member to deliver ammonia to the base, a larger hole also extending through said member to receive the ascending gases, and a discharge tube secured to the vertical member, in communication with the larger hole, said tube extending well into the interior of the vessel and being circumferentially slotted at its upper end to discharge the gas therein in a diffused manner.

3. In a device of the type specified, the combination with a frame, a heating chamber at the bottom thereof, of an elongated ammonia-receiving vessel, a chambered base therefor insertible into an opening in said heating chamber, gravity means for delivering ammonia from said vessel to its base, means for conducting the generated gas from said base to the interior of said vessel, a clamping device for securing the top portion of said vessel to said frame, and a connecting tube formed in said frame, for communicable engagement with the top portion of said vessel after the latter is clamped to the upper portion of said frame.

4. In a device of the type specified, the combination with a frame, a heating chamber at the bottom thereof, of an elongated ammonia-receiving vessel, a relatively small chambered base therefor insertible into an opening in said chamber, a vertical member of reduced diameter connecting said vessel and base, a conduit in said member for conducting liquid ammonia from said vessel to its base, a larger conduit in said member for conducting ammonia gas from said base to the vessel, an elongated neck portion between the upper and lower ends of said vessel to coöperate with the vertical member in cooling the upper end of the latter, and a gas outlet therein well above said reduced neck portion.

5. In a device of the type specified, the combination with a frame, a heating chamber forming the bottom thereof, of an elongated ammonia-receiving vessel having two enlarged end portions connected by an integral elongated neck portion, an outwardly flaring mouth at one side of the upper end portion of said vessel, a relatively small chambered base for the latter insertible into an opening in said heating chamber, a vertical member of reduced diameter connecting the lower end of said vessel with its chambered base, a conduit in said vertical member for conducting liquid ammonia from said vessel to its base, a parallel, but larger, conduit in said member to receive the

ascending ammonia gases, a slotted tube in communication with the second conduit for discharging said gas into the upper portion of the lower end of said vessel, inclined baffle plates in the upper end of the vessel, a gas outlet above the baffle plates, a clamping device for securing the upper end of said vessel to the frame, and a connecting tube in said frame adapted to communicate with

the gas outlet when the upper end of the 10 vessel is clamped to the frame.

In testimony whereof I have hereunto set my hand this 8th day of November, 1917.

CARL F. SCHEFFER.
